(57) **CLAIM**

We claim the ornamental design for a squirt gun, as shown and described.

DESCRIPTION

FIG. 1 is a perspective view of a squirt gun according to the present invention.

FIG. 2 is a top perspective view of the squirt gun of FIG. 1.

FIG. 3 is a front view of the squirt gun of FIG. 1.

FIG. 4 is a right side view of the squirt gun of FIG. 1.

FIG. 5 is a left side view of the squirt gun of FIG. 1.

FIG. 6 is a rear view of the squirt gun of FIG. 1.

FIG. 7 is a top view of the squirt gun of FIG. 1; and,

FIG. 8 is a bottom view of the squirt gun of FIG. 1.

Portions of the squirt gun that are not shown in the drawing(s) form no part of the claimed design.

The broken lines are for illustrative purposes only and form no part of the claimed design.
